US00D815283S

(12) **United States Design Patent** (10) **Patent No.:** **US D815,283 S**
(45) **Date of Patent:** **** Apr. 10, 2018**

(54) **PROSTHESIS**

(71) Applicant: **OTTO BOCK HEALTHCARE GMBH**, Duderstadt (DE)

(72) Inventor: **Christian Noack**, Göttingen (DE)

(73) Assignee: **OTTO BOCK HEALTHCARE GMBH**, Duderstadt (DE)

(**) Term: **15 Years**

(21) Appl. No.: **35/500,869**

(22) Filed: **Oct. 28, 2015**

(80) **Hague Agreement Data**

Int. Filing Date: **Oct. 28, 2015**

Int. Reg. No.: **DM/088538**

Int. Reg. Date: **Oct. 28, 2015**

Int. Reg. Pub. Date: **Apr. 29, 2016**

(30) **Foreign Application Priority Data**

Apr. 29, 2015 (EM) 002692087

(51) **LOC (11) Cl.** **24-03**

(52) **U.S. Cl.**

USPC **D24/155**
